RECLOSING CIRCUIT INTERRUPTER

James M. Wallace, Braddock, and Herbert L. Rawlins, Wilkinsburg, Pa., assignors to Westinghouse Electric Corporation, East Pittsburgh, Pa., a corporation of Pennsylvania

Application January 16, 1941, Serial No. 374,686

43 Claims. (Cl. 200—89)

1

This invention relates generally to circuit interrupters, and more specifically to operating mechanism and control means for circuit interrupters.

Although this invention is herein specifically disclosed in connection with an automatic reclosing circuit breaker capable of automatic lockout in response to a predetermined number of closely successive interrupting operations, wherein the invention has certain novel features of cooperation providing certain new and useful results, it will be appreciated that certain features of the invention may also be useful in connection with other types of circuit breakers, and even apparatus other than circuit breakers.

In order to obtain better coordination with other breakers of the automatic reclosing type, it is desirable that the breaker have an inverse time characteristic, which preferably shall be the same for all trippings of the breaker.

Accordingly, one object of this invention is to provide novel means for providing an inverse time delay tripping characteristic for a circuit breaker.

Another object of this invention is to provide novel trip control means for an automatic reclosing circuit breaker which shall provide the same tripping characteristics on all trippings of the breaker.

In the copending application of J. M. Wallace, Serial No. 374,684, filed January 16, 1941, and issued June 20, 1944, as Patent No. 2,352,048, assigned to the same assignee as this invention, there is disclosed a reclosing circuit breaker having time delay reclosing means associated with a contact opening means, which has a resilient lost motion connection with the movable contact, to insure a time delay on each reclosure of the breaker. In accordance with this invention a positive lost motion is provided between the movable contact and the contact separating means, to insure a substantially constant time delay on each reclosure of the breaker.

Therefore, another object of this invention is to provide in a breaker of the type described, novel means for providing a uniform time delay on each reclosure of the breaker.

Another object of this invention is to provide in a circuit breaker of the type described, novel mechanism for controlling the opening and closing movements of the breaker.

Another object of this invention is to provide in a breaker of the type described, novel means for maintaining the breaker contacts separated in

2

response to a predetermined number of closely successive reclosures thereof.

These and other objects of this invention will become more apparent upon consideration of the following description of preferred embodiments thereof when taken in connection with the attached drawings, in which:

Fig. 1 is a substantially central, longitudinal sectional view of a circuit breaker embodying this invention.

Fig. 2 is a view like Fig. 1 only showing the position of the parts after a circuit interrupting operation.

Fig. 3 is a partial, substantially central, longitudinal section view of the breaker shown in Figs. 1 and 2, and taken substantially at right angles to the section of Figs. 1 and 2.

Fig. 4 is a view similar to Fig. 1, showing a portion of the upper end of the breaker with the parts positioned to lock the breaker contacts open.

Fig. 5 is a view of a modified form of interrupter operating mechanism per se, with certain parts thereof in section.

Fig. 6 is an enlarged partial side elevational view of the mechanism shown in Fig. 5.

Fig. 7 is an enlarged partial elevational view of the mechanism shown in Fig. 5, looking at the opposite side thereof, and

Fig. 8 is an elevational view, partly in section, of a still further modified form of circuit breaker operating mechanism.

The several embodiments of this invention herein disclosed, are adapted to be mounted in an insulating casing 2 having an upper terminal cover assembly 4, and a lower terminal assembly 6, which are substantially like those disclosed in applicants' copending application, Serial No. 346,300, filed July 19, 1940, issued May 4, 1943 as Patent No. 2,318,421, and assigned to the same assignee as this invention. Accordingly, for a more complete description of these parts, and for a full understanding of their function, reference is hereby made to the above-mentioned copending application.

In general, the insulating housing 2 is tubular or cylindrical in form, and is provided with an open top and a closed bottom. An intermediate portion of the casing 2 is adapted to have a supporting bracket 5 secured thereto, for supporting the breaker in operative position. The upper cover terminal assembly 4 includes the cover 8, having a diametrically extending hollow portion for the reception of certain parts of the breaker operating mechanism. The cover 8 is also pro-

vided with a peripheral flange 10 adapted to be seated on the open end of casing 2, and secured to an annular support 12 by any desired connecting means (not shown).

The lower terminal assembly 6 includes a bolt 14 of any desired conducting material, having an enlarged head 16 adapted to be positioned within casing 2, with packing material 18 between head 16 and the closed end of the casing. Conducting bolt 14 extends through a substantially central aperture in the closed end of casing 2, and is provided with a nut 20 for securing the bolt in operative position, with a washer 22 interposed between the nut and outer wall of the casing. As shown, a terminal strap 26 may be secured to bolt 14, for example, as by nut 28. The bolt 14 is also provided with a small central bore 24, adapted to have the outer end thereof closed by a removable drain plug 25, so that the casing may be drained when desired.

The circuit breaker and its operating mechanism are adapted to be supported from cover 8 by a pair of spaced supporting plates 30, secured to a portion of cover flange 10 overlying the interior of casing 2, for example, as by bolts 32, and these plates are connected by transversely extending integral frame portions 34 and 36. Spaced supporting plates 40, positioned substantially at right angles to supporting plates 30, are formed integral with transverse frame portion 36 and extend downwardly therefrom to support an interrupting chamber 42. The lower ends of supporting plates 40 are rigidly secured together by an integral web 38, having a socket 46 integral therewith for threadedly receiving one end of insulating tube 44, forming the side wall of interrupting chamber 42. Insulation tube 44 may be of any desired insulating material, preferably fiber or the like. The other end of insulation tube 44 is provided with an end terminal cap 48 threadedly engaged therewith, and conductively and resiliently associated with the enlarged head 16 of the lower terminal assembly bolt, by coil compression spring 50. Spring 50 is preferably of a resilient conducting material, such for example, as a copper alloy.

It will be noted that the interrupting chamber is provided with an outlet valve 52 and an inlet valve 54, a contact support 56 slidably mounted in a central aperture through transverse support frame member 38, together with a contact 58 mounted thereon, and a liquid director 60 having a resilient lost motion with respect to contact 58. This interrupter chamber structure is substantially the same as that disclosed in the above-mentioned copending patent of J. M. Wallace. The only difference in construction of the interrupter chamber of this invention over that disclosed in the Wallace Patent, is that the contact support 56 is of insulation material for a purpose hereinafter to be described, and fixed contact 62 is mounted for limited relative movement with respect to end terminal cap 48, by a screw 64, secured to fixed contact 62 with the reduced intermediate portion thereof slidably extending through a central aperture in end cap 48, to provide for movement of contact 62 limited by the head of screw 64 and the contact itself, and normally biased upwardly by a coil compression spring 66 seated between end cap 48 and a shoulder formed on contact 62. Also, contact support 56 is formed with a notched portion 68 adjacent the upper end thereof for a purpose to be referred to.

In operation, interrupter 42 operates substan-

tially in the same manner described in the Wallace patent. This, in general, is as follows: When contact support 56 is moved upwardly to open the circuit, contact 58 moves away from fixed contact 62, after the head of screw 64 engages the lower terminal cap 48, to draw an arc therebetween. As soon as upward motion of contact support 56 is initiated, valve 52 moves therewith to close off the outlet of the interrupter casing. All this time liquid director 60 remains stationary, being held in the position shown in Fig. 1 by the spring 61 between contact support 56 and the director. As soon as the limit of the lost motion between the contact and director 60 is reached, the contact will pick up the liquid director and move the same upwardly to thereby cause a stream of arc extinguishing fluid to flow through the arc to aid in extinguishing the same. After the circuit has been interrupted and contact support 56 is moved downwardly to close the circuit, valve plate 52 will be moved therewith to open the chamber outlet, and check valve plate 54 will be raised to permit liquid to flow in the chamber inlet under the influence of gravity. As the contact approaches closed position, liquid director 60 is first brought to a halt, and thereafter coil spring 61 is compressed and finally contact 58 engages fixed contact 62.

Contact support 56 is adapted to be disengaged by an elongated contact rod 70, having one end thereof threadedly engaged in a bore in the upper end of contact support 56, and the other end thereof threadedly secured in the lower end of a socket member 72, forming one element of a contact locking means. As shown, the socket 72 is hollow in form, and is provided with opposed slots through which are adapted to project the locking projections 76, of a pair of locking dogs 74 pivotally mounted at their lower ends on a pin 75 extending transversely of socket 72. The locking dogs 74 are proportioned so that the major portion of their mass lies on opposite sides respectively of a vertical plane through pivot 75, so that the dogs are biased by gravity to a projecting position with respect to socket 72. The upper end of socket 72 is adapted to fit into a bore provided in a cooperating inverted locking socket 80, having opposed side apertures 78 for the reception of lock projection 76 on the locking dogs, to secure the two socket portions for movement together. It will be noted that the upper socket 80 is adapted to be slidably mounted in a sleeve 82 secured in a central aperture in upper transversely extending support plate 34. It will be further noted that in the closed position of the contacts, the locking projections 76 on the locking dogs, are adapted to extend through apertures 78 of the upper socket member, to lie beneath and in engagement with the lower end of sleeve 82 to thereby maintain the contacts locked in their closed circuit position.

The upper end of socket 80 is slotted to form bifurcations 84 for supporting therebetween an actuating pin 86. This pin is adapted to be engaged by a reclosing lever 88, pivotally supported as at 90 in the hollow portion of cover 8, and provided with a biasing spring 92 normally urging lever 88 in a counterclockwise direction about its pivot, to close the breaker contacts. The outer end of reclosing lever 88 is inclined or curved to cooperate with the top of actuating pin 86. Biasing spring 92 also causes engagement of socket 80 with locking dogs 74 to assist in biasing them relatively outwardly.

A substantially cylindrical solenoid core 94, of

any desired magnetic material, is adapted to be slidably mounted at the lower end thereof on contact rod 70. The core 94 is provided with an outwardly projecting flange 96 at the lower end thereof, and with a counter bore 98 opening at the upper end thereof for the reception of a coil spring 100. A solenoid coil 102 is adapted to be supported between the transversely extending supporting plate portions 34 and 36, of the supporting frame, and this coil preferably is annular in form to provide a central bore therethrough in which is adapted to be mounted a cylindrical sleeve 104, preferably of a non-metallic material, such, for example, as fiber, a synthetic resin or the like.

It will be noted that solenoid core 94 slidably engages cylindrical sleeve 104 in a piston-like manner, and inasmuch as the entire mechanism is submerged in an arc extinguishing fluid which fills container 2 substantially up to the level L, and further in view of the fact that the upper end of cylinder sleeve 104 is closed, it will be obvious that upon energization of solenoid coil 102 sufficiently to raise core 94, that this movement of the core will be retarded by the dashpot action formed by the core and cylindrical sleeve 104. In other words, when core 94 is drawn upwards by solenoid coil 102, it is necessary that the liquid above the core in cylindrical sleeve 104 be forced out of the lower end of sleeve 104 past the relatively small clearance between the core and sleeve 104, which will necessarily delay the upward movement of core 94. This delayed action of course, will be dependent upon the current passing through solenoid coil 102, so that the desirable inverse time characteristic is obtained for opening the breaker contacts.

As solenoid core 94 is moved upwardly in a circuit interrupting operation, it will be obvious that contact rod and contact 58 are maintained stationary by locking dogs 74, and that eventually in the upward movement of the core, coil spring 100 will engage the lower end of socket 72, so that upon continued upward movement of the core this spring will be compressed. The upper end of core 94 will eventually engage the lower end of upper socket 80, to move the same upwardly relative to lower socket 72, so that the lower edges of apertures 78 will act to cam locking dogs 74 inwardly, and permit contact rod 70 to be released. At this point there will be a positive drive connection between solenoid core 94 and contact rod 70, and because of the compressed condition of coil spring 100 which is of greater strength than contact closing spring 92, the contact 58 will be moved relatively quickly away from fixed contact 62, and this action will also be aided by any pressures developed by the arc within interrupter chamber 42. It should be noted that the contacts separate only a predetermined time subsequent to the initiation of movement of solenoid core 94, which time is predetermined by the dashpot action of the core and cylindrical sleeve 104, and dependent on the current through solenoid 102. This provides a time delay on tripping the breaker, which has been found experimentally to be as much as three seconds at minimum trip current values.

After the circuit has been interrupted, the contact rod 70 is free to be moved downwardly under the influence of contact closing spring 92, through lever 88 acting on pin 86. However, between spaced supporting plates 40, adjacent to and just above the interrupting chamber 42, there are pivoted a pair of latch levers 106, on pivot pins 107

extending between the supporting plates, with each lever having a projection 109 adapted to engage the notch 68 at the upper end of contact support 56, to maintain the contacts open for a predetermined time period.

The latch levers 106 are biased towards each other to engage in notch 68 by a coil tension spring 108, connecting the levers at one side thereof. Accordingly, it will be seen that the contact closing spring 92 will immediately move the contact rod downwardly to a position wherein it is prevented from further movement by latch levers 106, and at this position the gap between contacts 58 and 62 will be sufficient to hold circuit voltage.

Meanwhile, solenoid core 94 will travel downwardly very slowly due to the fact that it must draw oil into the space above it as it is moved downwardly under the influence of gravity, until the flange 96 on solenoid core 94 engages the upper inclined ends of latch levers 106, to spread these levers apart and release contact 58 to permit the contacts to suddenly close. Consequently, it can be seen that a time delay is interposed between the actual interruption of the circuit and the reclosure of the breaker contacts by the dashpot action of solenoid core 94 in cylindrical sleeve 104. It has been determined that such a time delay in the reclosing operation may be made as long as ten to twelve seconds.

It will be apparent from the foregoing that there is incorporated in this embodiment of the invention a solenoid core which acts as one element of an inverse time current delay means for the circuit interrupting operation, and also provides a delay between the interrupting operation and reclosure of the breaker contacts. This embodiment of the invention further includes the feature of locking the breaker contacts in their closed circuit position, so that upon the occurrence of predetermined conditions in the circuit, an operating means for the contacts is first moved relative thereto to provide time delay in the interrupting operation and to stress a resilient means for biasing the contacts open, and only thereafter releasing the contact lock to permit them to separate.

The inner surface of transversely extending supporting plate 36 is provided with a relatively large cylindrical portion 111 adapted to receive flange portion 96 on solenoid core 94 when the core is adjacent the upper end of its path of movement. This cylindrical bore portion 111 is provided with a transverse outlet passage 110 connected to a cylinder 112, integral with upper and lower transverse supporting plates 34 and 36, with a resiliently biased check valve 114 controlling said passage to permit flow of liquid from cylindrical bore 111 into cylinder 112. A spring 116 is provided for biasing valve 114 to close passage 110, and a free floating piston 118 is preferably positioned in cylinder 112.

A lock-out lever 120 is secured to an operating shaft 124 extending transversely of the hollow portion of cover 8, with one end thereof extending through one wall of said hollow portion to have secured thereto a manually operable actuating lever 132. The lock-out lever 120 is biased for movement in a counter-clockwise direction with respect to the axis of shaft 124, by a spring 122 coiled about the shaft and engaged at its opposite ends with the cover 8 and lever 120, respectively. The free end of lock-out lever 120 is curved and positioned below actuating pin 86. The coil spring 122 of the lock-out lever 120 is considerably stronger than the contact reclosing

spring 92, but is normally prevented from effecting operation of the contacts by a shoulder portion 126 integral with lever 120, being engaged by one leg 128 of a trigger lever pivotally mounted on the cover as at 129, and having the other leg 130 extending downwardly and provided with an inclined free end positioned over the top of cylinder 112.

Now, when the solenoid core 94 is moved upwardly as was previously described, to interrupt the circuit, when it reaches the end of its upward movement, flange portion 96 will act as a piston in cylinder portion 111 and force a predetermined quantity of liquid through passage 110, past check valve 114 and into cylinder 112, thereby raising piston 118 a predetermined distance in the cylinder, for example to the position shown in Fig. 2 of the drawings.

Now, when the contacts are reclosed by contact closing spring 92, if the fault has been removed from the circuit, piston 118 will slowly return to the position shown in Fig. 1 of the drawings, under the influence of gravity, and being delayed by the necessity of displacing the liquid below the piston past the relatively small clearance between the piston 118 and cylinder 112. However, if after the first reclosure of the breaker contacts the fault still remains on the circuit, the contacts will again be opened in the same manner as for the first time, and this time flange 96 will act to force another predetermined quantity of liquid into cylinder 112 to advance piston 118 nearly to the top of the cylinder 112. Upon a second closely successive reclosure of the breaker, if the fault has cleared by this time, the piston 118 will again slowly move to its normal position shown in Fig. 1 of the drawings. However, in the event that the fault has not cleared from the circuit, the contacts will again reopen, and this time flange 96 on solenoid core 94 will force sufficient liquid into the cylinder 112 to raise the piston 118 into engagement with the inclined end of trigger lever 130, to rotate this lever in a counter-clockwise direction about its pivot 129, to release lock-out lever 120 for movement in a counter-clockwise direction under the influence of its spring 122, and cause it to raise contact rod 10 against the bias of contact closing spring 92, as shown in Fig. 4, and thereby prevent further reclosures of the breaker contacts.

In order to reset the circuit breaker, it is necessary to exert a manual push on lever 132 to rotate it and lock-out lever 120 in a clockwise direction, until shoulder 126 on the lock-out lever is re-engaged by leg 128 of the trigger lever. Inasmuch as piston 118 will have in the interim descended from the position shown in Fig. 4 to its normal position shown in Fig. 1, the contacts may then be closed by reclosing spring 92 and thereby restored to normal operating condition.

The electrical circuit through the breaker may be traced from lower terminal assembly 6, to coil spring 50, lower interrupter casing terminal cap 48, fixed contact 62, movable contact 58 to a conductor 131 extending upwardly through a bore 133 provided off center through contact support 56 to one lead of solenoid coil 102. The other lead of solenoid coil 102 is adapted to be connected by a conductor 137 to cover 8, for example, as by bolt 32, and the other terminal of the breaker is adapted to be suitably mounted on cover 8. It can, therefore, be seen that with this construction the solenoid coil 102 is connected in series relation in the circuit through the breaker, so as to be responsive to overload currents

to cause movement of core 94 to interrupt the circuit.

Coordination between breakers of different ratings is readily obtainable with this device. In order to have different ratings of breakers, a different number of turns is wound for solenoid coil 102. Thus, for example, for a 20-ampere breaker approximately 250 turns may be required for the solenoid coil, while for a 40-ampere breaker only 125 turns may be required. Considering now a fault current flowing through the two breakers in series on a line, it will be obvious that twice as many ampere turns will be available for moving the solenoid core 94 in the 20-ampere breaker than in the 40-ampere breaker. Consequently the core of the 20-ampere breaker will move much faster, so that this breaker will be tripped and clear the circuit before the solenoid core in the 40-ampere breaker can complete its stroke. The solenoid core in the larger breaker will therefore cease its upward travel and both solenoid cores will start to reset. Inasmuch as the breaker of a larger rating will have had the shorter core travel, its core will completely reset before the contacts of the smaller breaker are reclosed to subject the two breakers to overload current again. Accordingly, it can be seen that the larger rating breaker will never trip under the circumstances described above, and the smaller breaker will lock out and isolate the faulted circuit.

The species of breaker illustrated in Figs. 5 to 7 of the drawings is adapted to be provided with an interrupting chamber like the interrupting chamber 42 of the species shown in Figs. 1 to 4, and it is also adapted to be mounted in operative relation with respect to a circuit breaker casing by a cover 8 adapted to clamp ears 135 on the mechanism supporting frame to the top wall 40 at the open end of the casing. As shown in Fig. 5, the supporting frame for this circuit breaker includes a substantially rectangular upper supporting portion having a top wall 134, spaced integral side walls 136 and a bottom wall 138. Depending from this rectangular supporting portion are spaced supporting plates 140 adapted to be connected at their lower ends by an integral socket 141 for connection to an interrupting chamber like that shown in Figs. 1 and 2 of the drawings. The contact rod 142 in this embodiment of the invention is provided with stepped portions at the upper end thereof forming relatively stepped shoulders 144 and 146, for cooperation with a solenoid core 150, which, like core 94, is adapted to be slidably mounted in a cylindrical sleeve 156, to form a dashpot therewith, and have a hollow bore with a spring therein as in the embodiment of Figs. 1 to 4, so that the spring will engage shoulder 144, and the core engage the shoulder 146, substantially in the same manner as in the previously described embodiment.

The upper end of contact rod 142 is adapted to be slidably mounted in a plug member 148 secured to upper frame member 134 for closing the upper end of cylindrical sleeve 156 and a solenoid coil 152 is adapted to be supported in the rectangular supporting frame portion.

Depending supporting plates 140 are each provided with aligned spaced guide slots 158 and 160 for receiving a guide pin 162 fixed on solenoid core 150, and a guide pin 164 fixed to contact rod 142, respectively. These guide pins are adapted to extend through their respective slots, 75 and through slots provided in a locking lever 166

mounted at the outer side of the adjacent supporting plate 140, intermediate the ends thereof on a pivot pin 168. Locking lever 166 is normally biased by a spring 170 for movement in a clockwise direction on its pivot pin. Locking lever 166 is also provided with the slots for receiving guide pins 162 and 164, respectively, with the upper slot 171 for receiving pin 162 being flared outwardly in an upward direction, and including an outer inclined end 172 for a purpose to be described. Slot 174 is provided with an angularly extending portion 176 normally adapted to receive guide pin 164 on contact rod 142, for preventing upward movement of the contact rod. A pawl lever 178 is pivotally mounted at its lower end on guide pin 164 and is biased by a spring 181 towards a rack 188. The pawl lever 178 is provided with a pawl projection 179 adjacent the upper end thereof extending laterally from the lever and supported from the lever by a portion having inclined surfaces 180 and 182 adapted to be engaged by stationary cam pins 184 and 186, respectively. The rack 188 is secured to the upper end of a piston 190, slidably mounted in a cylinder 192 supported on the supporting frame socket 141. A light coil compression spring 194 is adapted to be positioned in the bottom of cylinder 192 for moving piston 190 to an extended position.

In the operation of this embodiment of the invention, upon the occurrence of an overload in the circuit, solenoid coil 152 moves core 150 upwardly until guide pin 162 on the core hits the inclined end 172 of slot 171 in the locking lever, thereby causing counter-clockwise rotation of the lever about its pivot 168, and releasing guide pin 164 on contact rod 142 to permit the solenoid to move the contact rod upwardly, aided, of course, by its spring which has been compressed by relative movement of the solenoid core and contact rod and by pressure in the interrupter chamber. After the circuit has been interrupted and the contacts are reclosed, preferably by a biasing means substantially like that shown in the first embodiment of this invention, as contact rod 142 moves downwardly, pawl projection 179 engages rack 188 to move the same downwardly a predetermined distance with the contact rod, which causes a time delay in reclosure due to the necessity of displacing liquid in the bottom of the cylinder 192 past the relatively small clearance between the piston and cylinder. Adjacent the end of the closing operation, inclined surface 182 on the pawl lever will engage cam pin 186 to cause the pawl lever to disengage rack 188, and allow the contacts to be suddenly closed. If the fault has cleared upon reclosure of the contacts, rack 188 will be raised to its extended position as determined by pin 185, working in slot 187 of the rack. However, if the fault has not cleared, the contacts will again be opened in the same manner as for the first interruption, and this time upon reclosure of the contacts, pawl lever 178 will move rack 188 and piston 190 down into cylinder 192 a further distance into close proximity with the lower end of cylinder 192. If, after this second reclosure, the fault has cleared, rack 188 will again be reset by spring 194. However, if the fault has not cleared, the breaker contacts will again be opened, and this time upon attempted reclosure thereof, pawl lever 178 will move rack 188 downwardly until the upper end of slot 187 engages fixed pin 185, thereby preventing further closing movement of the breaker contacts.

In order to reset the breaker to normal oper-

ating condition it is necessary to raise contact rod 142 until inclined surface 180 on pawl lever 178 engages cam pin 184, to disengage pawl projection 179 from rack 188, to thereby permit the rack to move upwardly, whereupon the contact rod 142 may be released, and the contacts reclosed as previously described.

In the modification of the invention shown in Fig. 8, there is illustrated a supporting frame comprising spaced supporting plates 196 joined by intermediate spaced transversely extending frame portions 197, 198 and 200, respectively. A solenoid coil 202 is adapted to be supported on the frame portion 197 between supporting plates 196. A contact rod 204 is secured to an enlarged rod portion 206 at the upper end thereof, to form a shoulder 208 adapted to be engaged by solenoid core 210 upon upward movement thereof. The solenoid core 210 is slidably mounted on the rod, and is provided adjacent the lower end thereof with a notch 212 adapted to be engaged by a latch 214 pivotally mounted on a time delay sleeve member 216, also slidably mounted on contact rod 204. The latch 214 is preferably supported on a pivot 218 on time delay sleeve 216, and is biased for movement to engage in notch 212 of the core, for example, as by a spring 220. Between transversely extending supporting plate portions 198 and 200, and also for a substantial distance below plate 200, there is provided a cylindrical wall portion integral with supporting plates 196 to form a cylindrical compartment 222 in which a time delay valve member 224 is adapted to work in a piston-like manner. Below supporting plate 200 a lock-out piston member 226 is adapted to operate. The time delay valve piston 224 is provided with passages 228 therethrough and a valve plate 230 biased to a position to close off passages 228, by a coil compression spring 232. The valve piston 224 is preferably fixed to time delay sleeve 216 for movement therewith. A check valve 234 is adapted to control an inlet passage 236 into the lower portion of cylinder compartment 222.

Lockout piston 226 is annular in form, and is provided with an inclined inner surface 238, for cooperation with a lockout lever 240, normally biased by a coil tension spring 242 to the position shown in Fig. 8 of the drawings.

The particular mechanism illustrated in Fig. 8 is, of course, adapted to be employed with an interrupter similar to the interrupter 42 shown in Figs. 1 to 4 of the drawings, and in conjunction with spring contact reclosing means also shown in the first described embodiment of this invention. In operation, when solenoid core 210 is attracted upwardly by solenoid coil 202, time delay sleeve 216 is carried along by virtue of the interconnection of latch 214 with core 210. This upward movement is therefore impeded to some extent by the necessity of liquid passing from the upper portion of cylinder compartment 222 to the lower portion thereof, through restricted passages 228, and liquid may be drawn into the lower portion of cylinder compartment 222 through restricted inlet passage 236. After predetermined movement of solenoid core 210, however, the outwardly extending projection 215 of latch lever 214 engages integral stop 217 on frame supporting plate 196, to release the solenoid core from the time delay sleeve 216. This permits the core to rise rapidly into engagement with shoulder 208 on the contact rod and separate the contacts.

It will be noted that the lower end of time

11

delay sleeve 216 is notched as at 244, and carries a latch lever 246 adapted to engage beneath integral shoulder 248 on contact rod 204, when the contact is adjacent the upper limit of its movement. Latch lever 246 is normally biased in a direction to engage shoulder 248, by a spring 250. Therefore, upon attempted movement of contact rod 204 in a downward direction to reclose the breaker contacts, this motion is impeded by valve member 224 which now has the passages 228 therethrough closed off by valve 238, so that all of the liquid therebelow in chamber 222 must be displaced through the relatively small clearance between the valve piston and cylinder chamber wall. Accordingly, a time delay is interposed between the circuit interrupting operation and reclosure of the circuit breaker contacts, until extension 252 on latch lever 246 engages integral stop 254 on supporting plate 196, to disengage the latch from contact rod shoulder 248 to permit quick reclosure of the contacts.

It will be noted that in the circuit closing operation a certain amount of the liquid contained in the lower part of cylinder compartment 222 will be forced through passages 256 in transverse supporting wall 200, to force lockout piston 226 downwardly a predetermined distance. In the event of a continuing fault on the circuit, lockout piston 226 will be forced downwardly a predetermined distance by each successive reclosure of the breaker contacts, until finally the inclined surface 238 thereof engages lockout lever 240 to move it in a clockwise direction about its pivot 241, into engagement with notch 244 on time delay sleeve 216, to thereby prevent movement of the same and contact rod 248 downwardly to a closed circuit position. Of course, if at any time before the predetermined number of reclosures of the breaker necessary to lock the contacts open, the fault clears, then lockout piston 226 will be slowly reset by coil spring 227 to its normal position shown in Fig. 8.

It will be noted that in this embodiment of the invention, a single time delay means is provided for both giving inverse time current characteristics on a circuit interrupting operation, and for delaying reclosing of the breaker contacts after an interrupting operation, and that this time delay means has different characteristics for these two operations, respectively; that is, the valve member 224 presents greater resistance in downward movement in compartment 222 by virtue of closure of valves 238, than its resistance to upward movement in cylinder compartment 222, because on this latter movement valve 238 is opened as well as inlet check valve 234.

The modifications of this invention shown in Figs. 5 to 8 are not specifically claimed here but are claimed in an application Serial No. 623,125, filed October 18, 1945, which is a division of this application.

In the foregoing there have been described several embodiments of the present invention incorporated in automatic reclosing circuit breakers of the fluid type, which are adapted to automatically reclose the circuit a predetermined number of times, after which the breaker contacts are automatically locked in an open circuit position, such as to require a manual operation to restore the breaker to operative condition.

Having described preferred embodiments of the invention in accordance with the patent statutes, it is desired that the invention be not limited to the particular embodiments herein disclosed, inasmuch as it will be obvious, particularly to per-

12

sons skilled in the art, that many modifications may be made in these particular embodiments without departing from the broad spirit and scope of the invention.

We claim as our invention:

1. In an automatic reclosing circuit interrupter, cooperating contact means one of which is mounted on a slidable contact supporting means for movement therewith into and out of engagement with the other of said contact means, an actuating sleeve limitedly slidably mounted on said supporting means, a cylindrical guide in which said sleeve is slidably mounted to form fluid time delay means for actuating said contacts a predetermined time after initiation of movement of said sleeve, said movable contact means being biased into engagement with said cooperating contact means to automatically reclose said contacts after a circuit interrupting operation, fluid operated lockout means adapted when advanced a predetermined amount from a normal position to prevent reengagement of said contact means, and fluid pumping means operable by said sleeve adjacent the end of its contact opening movement to advance said lockout means an amount less than said predetermined amount whereby said contacts are locked in an open circuit position in response to a predetermined number of circuit interrupting operations thereby.
2. In an automatic reclosing circuit interrupter, separable contacts, said contacts being biased into engagement to automatically reclose said contacts after a circuit interrupting operation, resilient means operative to overcome said bias to maintain said contacts separated a predetermined amount, releasable holding means for preventing operation of said resilient means, electro-responsive means for causing separation of said contacts independently of said resilient means to interrupt the circuit, means responsive to a predetermined number of circuit interrupting operations to release said holding means, and manually operable means for resetting said resilient means to permit reclosure of said contacts.
3. In an automatic reclosing circuit interrupter, cooperating contact means one of which is mounted on a slidable contact supporting means for movement therewith into and out of engagement with the other of said contact means, an actuating sleeve limitedly slidably mounted on said supporting means, a cylindrical guide in which said sleeve is slidably mounted to form fluid time delay means for actuating said contacts a predetermined time after initiation of movement of said sleeve, said movable contact means being biased into engagement with said cooperating contact means to automatically reclose said contacts after a circuit interrupting operation, fluid operated lockout means adapted when advanced a predetermined amount from a normal position to prevent reengagement of said contact means, fluid pumping means operable by said sleeve adjacent the end of its contact opening movement to advance said lockout means an amount less than said predetermined amount whereby said contacts are locked in an open circuit position in response to a predetermined number of circuit interrupting operations thereby, said pumping means including a piston flange at one end of said sleeve adapted to be received in an enlarged cylinder portion on said cylindrical guide adjacent the end of contact opening movement of said sleeve.
4. In a circuit interrupter, cooperating contact means one of which is mounted on a slidable con-

tact supporting means for movement therewith into and out of engagement with the other of said contact means, an actuating sleeve limitedly slidably mounted on said supporting means, a cylindrical guide in which said sleeve is slidably mounted, said movable contact means being biased into engagement with said cooperating contact means, fluid operated lockout means adapted when advanced a predetermined amount from a normal position to prevent reengagement of said contact means, fluid pumping means operable by said sleeve adjacent the end of its contact opening movement to advance said lockout means an amount less than said predetermined amount whereby said contacts are locked in an open circuit position in response to a predetermined number of circuit interrupting operations thereby, releasable means locking said contact rod in engagement with said contact, releasable means locking said contact rod at an open circuit position, time delay means associated with said actuating means to delay movement thereof in opposite directions, each of said locking means having a part positioned in the path of movement of said actuating means and spaced from the ends of said path, respectively, whereby to release said contact rod to open the circuit only a predetermined time after initiation of movement of said actuating means in a direction to open the circuit, and to release said contact rod to close the circuit only a predetermined time after a circuit interrupting operation.

5. In a circuit interrupter, cooperating contact means one of which is mounted on a slidable contact supporting means for movement therewith into and out of engagement with the other of said contact means, an actuating sleeve limitedly slidably mounted on said supporting means, fluid actuated means adapted to maintain said contacts separated when advanced a predetermined amount, fluid pumping means adapted to be actuated in response to a circuit interrupting operation to advance said fluid actuated means an amount less than said predetermined amount, and said pumping including an enlarged piston portion on said sleeve and a cylinder portion positioned to receive said flange adjacent the end of circuit interrupting movement of said sleeve.

6. In an automatic reclosing circuit breaker, separable contacts, means responsive to predetermined electrical conditions for causing separation of said contacts, said contacts being biased into engagement independently of said condition responsive means to automatically reclose said contacts after a circuit interrupting operation at a rate solely determined by said bias, and time delay means adapted to be mechanically associated with at least one moving part of the breaker for delaying opening of said contacts for a predetermined time after the occurrence of said predetermined conditions, and for delaying closing movement of said contacts a predetermined time after a circuit interrupting operation.

7. In a circuit breaker of the character described, the combination of an operating mechanism, separable contacts at least one of which has two positions of repose one of which occurs when the circuit breaker is in its circuit closed position and the other of which occurs when the circuit breaker is in its open circuit position, separate means for retaining said one contact in each of said positions of repose, means operative at least as soon as said contact reaches said

open circuit position for exerting sufficient force on said contact to move it to closed circuit position but being prevented from doing so by said retaining means, means for releasing each of said retaining means under predetermined conditions of operation, whereby said operating mechanism may cause said circuit breaker to operate through a predetermined cycle of circuit opening and reclosing operations and a single timing means adapted to delay the release of said one contact by either of said retaining means after the occurrence of said predetermined conditions.

8. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, said movable contact being subjected to a biasing force sufficient to reclose the circuit at least as soon as it reaches full open circuit position, means for automatically detaining said movable contact against movement at an open circuit position against said reclosing bias, time delay means for determining the time said detaining means is effective after which said biasing force is effective to reclose the contacts and the circuit closing movement of said cooperating contact being solely influenced by the aforesaid biasing force.

9. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, said overload - responsive means being movable in response to overloads from a normal position a predetermined distance before causing separation of said contacts, said movable contact being subjected to a biasing force sufficient to reclose the circuit at least as soon as it reaches full open circuit position, means for automatically detaining said movable contact at an open circuit position against said reclosing bias, said overload-responsive means being biased to return to its normal position independent of the reclosing bias on said movable contact, said overload-responsive means adapted to release said detaining means after predetermined return movement, and time delay means governing the rate of movement of said overload-responsive means for at least a part of its movement in both directions, whereby said contacts are rapidly separated only a predetermined time after the occurrence of said overload and are rapidly reclosed only a predetermined time after a circuit interrupting operation.

10. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, releasable means for automatically holding said movable contact at its closed circuit position, said overload-responsive means being movable in response to overloads a predetermined distance before releasing said holding means and causing said movable contact to interrupt the circuit, said movable contact being subjected to a biasing force sufficient to reclose the circuit at least as soon as it reaches full

15

open circuit position, means for automatically detaining said movable contact at an open circuit position against said reclosing bias, a single time delay means for governing movement of said overload-responsive means and release of said detaining means, whereby said contacts are separated only a predetermined time after the occurrence of said overload and are reclosed only a predetermined time after a circuit interrupting operation and the circuit closing movement of said cooperating contact being solely influenced by the aforesaid biasing force.

11. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, releasable means for automatically holding said movable contact at its closed circuit position, said overload-responsive means being movable in response to overloads from a normal position a predetermined distance before releasing said holding means and causing separation of said contacts, said movable contact being subjected to a biasing force sufficient to reclose the circuit at least as soon as it reaches full open circuit position, means for automatically detaining said movable contact at an open circuit position against said reclosing bias, said overload-responsive means being biased to return to its normal position independent of the reclosing bias on said movable contact, said overload-responsive means adapted to release said detaining means in its return movement, and time delay means governing the rate of movement of said overload-responsive means for at least a part of its movement in both directions, whereby said contacts are separated only a predetermined time after the occurrence of said overload and are reclosed only a predetermined time after a circuit interrupting operation.

12. In an automatic circuit recloser, separable contacts, overload-responsive means for separating said contacts to interrupt the circuit, means for automatically reclosing said contacts after a circuit interrupting operation, normally inactive means adapted when activated to prevent reclosure of said contacts by said reclosing means, fluid-operated motor means adapted when advanced a predetermined amount from a normal position to activate said reclosure-preventing means, said motor means being biased to return to said normal position, said overload-responsive means comprising a solenoid coil and a core mounted for movement relative to said contacts, means positioned to be engaged by said core when at a point adjacent the end of its movement relative to said contacts when actuated by said coil to cause separation of said contacts, fluid pumping means, and means responsive to movement of said core to substantially said point in its path of movement to cause said pumping means to deliver the same predetermined quantity of fluid under pressure to said motor means on each circuit opening operation so as to advance said motor means an amount less than said predetermined amount, whereby to activate said reclosure-preventing means only in response to a predetermined number of closely successive circuit interrupting operations.

13. In an automatic circuit recloser, separable contacts, overload-responsive means for separating said contacts to interrupt the circuit, means for automatically reclosing said contacts after a

16

circuit interrupting operation, normally inactive means adapted when activated to prevent reclosure of said contacts by said reclosing means, fluid-operated motor means adapted when advanced a predetermined amount from a normal position to activate said reclosure-preventing means, said motor means being biased to return to said normal position, said overload-responsive means comprising a solenoid coil and a movable core mounted for movement relative to said contacts, means positioned to be engaged by said core when at a point adjacent the end of its movement relative to said contacts when actuated by said coil to cause separation of said contacts, pump cylinder means, and said core having a piston portion thereon positioned thereon so as to be received in said cylinder means only substantially at said point in its path of movement to deliver the same predetermined quantity of fluid under pressure to said motor means on each circuit opening operation to advance said motor means an amount less than said predetermined amount, whereby to activate said reclosure-preventing means only in response to a predetermined number of closely successive circuit interrupting operations.

14. In an automatic circuit recloser separable contacts, overload-responsive means for causing separation of said contacts to interrupt the circuit, means for automatically reclosing said contacts after a circuit interrupting operation, normally inactive means adapted when activated to prevent reclosure of said contacts by said reclosing means, integrating means responsive only to a predetermined number of closely successive circuit interrupting operations to be advanced a predetermined amount, means positioned to be engaged by said integrating means only when advanced said predetermined amount to activate said reclosure-preventing means, manually operable means operatively associated with said reclosure-preventing means and being mounted for movement independently of said integrating means and contacts for resetting said reclosure-preventing means, and said manually operable means even though held at resetting position being ineffective to prevent automatic operation of said contacts.

15. In an automatic reclosing circuit interrupter, separable contacts, electroresponsive means for separating said contacts and including an actuating member having a lost motion connection with said contacts, said contacts being continuously biased closed independent of said electroresponsive means, time delay means associated with said actuating member for delaying movement thereof, means for releasably securing said contacts closed, and said securing means adapted to be released in response to predetermined movement of said actuating member in a direction to separate said contacts, whereby said contacts are automatically separated in response to predetermined electrical conditions, and are moved into engagement solely by the force exerted by said bias to automatically close the circuit.

16. In an automatic reclosing circuit interrupter, separable contacts, electroresponsive means for separating said contacts and including an actuating member having a lost motion connection with said contacts, said contacts being continuously biased closed independent of said electroresponsive means, means for releasably securing said contacts closed, said securing means adapted to be released in response to predeter-

mined movement of said actuating member in a direction to separate said contacts, releasable means for automatically maintaining said contacts open after their separation by said actuating means, said actuating member biased for movement in an opposite direction, time delay means associated with said actuating member for delaying movement thereof in said directions, and said actuating means adapted to release said second contact securing means upon predetermined movement thereof in an opposite direction, whereby said contacts are automatically separated in response to predetermined electrical conditions, and are moved into engagement solely by the force exerted by said bias to automatically close the circuit.

17. In an automatic reclosing circuit interrupter, cooperating contacts one of which is movable into and out of engagement with the other of said contacts, said movable contact being biased into engagement with the other of said contacts to automatically reclose said contacts after a circuit interrupting operation, an abutment movable with said movable contact, resiliently biased means adapted to freely engage one side of said abutment for overcoming said closing bias to maintain said contacts separated, releasable holding means for preventing movement of said abutment by said resiliently biased means, electroresponsive means for causing separation of said contacts independently of said resiliently biased means to interrupt the circuit, means responsive to a predetermined number of circuit interrupting operations to release said holding means, and manually operable means for resetting said resiliently biased means to permit reclosure of said contacts.

18. In an automatic reclosing circuit interrupter, separable contact means, contact-actuating means comprising a piston member having lost motion relative to said contacts, means responsive to a predetermined circuit condition for moving said piston member in a direction to open the circuit, a tubular guide in which said member is slidably mounted to form fluid time delay means for controlling at least certain contact operation, means for automatically closing said contacts following a circuit opening operation thereof, fluid actuated means for maintaining said contacts separated when advanced a predetermined amount, a fluid pump piston actuated by said piston member, means for causing the pumping stroke of said pump piston to be less in extent than the extent of movement of said piston member so as to advance said fluid actuated means an amount less than said predetermined amount in response to each circuit interrupting operation of said interrupter.

19. In an automatic circuit recloser, separable contacts, overload-responsive means for causing separation of said contacts to interrupt the circuit, means for automatically reclosing said contacts after a circuit interrupting operation, normally inactive means adapted when activated to prevent reclosure of said contacts by said reclosing means, integrating means biased to a normal position and adapted to be advanced a predetermined amount on each circuit interrupting operation, said integrating means mounted for movement independent of said normally inactive means and arranged so that when advanced an amount greater than said predetermined amount by a plurality of closely successive circuit interrupting operations it will activate said reclosure-preventing means, the return movement of said

integrating means under the influence of its bias being independent of said reclosure preventing means, and manually operable means connected directly with said reclosure-preventing means for resetting said reclosure-preventing means.

5 20. In an automatic reclosing power circuit breaker, separable contacts, means unaffected by normal loads on the circuit through said breaker but responsive to overloads for causing separation of said contacts, means for automatically closing said contacts in response to a circuit interrupting operation, said overload responsive means having a part movable a predetermined amount in a circuit interrupting operation before said contacts separate, means for delaying movement of said part with an inverse time-current characteristic to delay separation of said contacts accordingly, means for causing said time delay means to retard automatic closing of said contacts, and means responsive to a predetermined number of closely successive circuit opening operations for preventing automatic closing of said contacts.

10 21. In an automatic reclosing power circuit breaker, separable contacts, means unaffected by normal loads on the circuit through said breaker but responsive to overloads for causing separation of said contacts, means for automatically closing said contacts in response to a circuit interrupting operation, said overload responsive means having a part movable a predetermined amount in a circuit interrupting operation before said contacts separate, means for delaying movement of said part with an inverse time-current characteristic to delay separation of said contacts accordingly, integrating means actuated solely in response to operation of said part so as to be responsive to a predetermined number of closely successive circuit opening operations for preventing automatic closing of said contacts.

15 22. In an automatic circuit recloser, separable contacts, overload-responsive means for causing separation of said contacts to interrupt the circuit, means for automatically reclosing said contacts after a circuit interrupting operation, resilient means operative when released to always hold said contacts separated a predetermined amount and prevent automatic reclosure thereof, releasable holding means normally preventing operation of said resilient means, and means responsive to a predetermined number of closely successive circuit interrupting operations to release said holding means.

20 23. In a circuit interrupter, cooperating contact means one of which is mounted for movement into and out of engagement with the other of said contact means, an actuating sleeve slidably mounted relative to said movable contact means, fluid actuated means adapted to maintain said contacts separated when advanced a predetermined amount, fluid pumping means adapted to be actuated in response to a circuit interrupting operation to advance said fluid actuated means an amount less than said predetermined amount, and said pumping means including an enlarged piston portion on said sleeve and a cylinder portion positioned to receive said piston portion only adjacent the end of circuit interrupting movement of said sleeve.

25 24. An automatic reclosing circuit breaker comprising a pair of contacts, said circuit breaker being permanently biased towards closed position, electromagnetic means for temporarily separating said contacts upon the occurrence of an electrical overload, operating means, said oper-

ating means being normally ineffective to separate said contacts, biasing means biasing said operating means more heavily than the bias of said circuit breaker, and means responsive to a number of successive operations of said circuit breaker for rendering said operating means effective for holding said circuit breaker open.

25. An automatic reclosing circuit breaker comprising a pair of contacts, electromagnetic means responsive to an electrical overload for separating said contacts, normally ineffective operating means for separating said contacts, said operating means having a part arranged in the path of travel of a portion of said circuit breaker for moving such portion to open said circuit breaker, cumulative hydraulic means responsive to a number of successive operations of said circuit breaker occurring in rapid succession for rendering said operating means effective, said operating means when released biasing and holding said contacts open, and pumping means actuated by said circuit breaker for pumping fluid into said cumulative hydraulic means.

26. An automatic reclosing circuit breaker comprising a pair of contacts, electromagnetic means responsive to an electrical overload for separating said contacts, normally ineffective operating means for separating said contacts, said operating means having a part arranged in the path of travel of a portion of said circuit breaker for moving such portion to open said circuit breaker, cumulative hydraulic means responsive to a number of successive operations of said circuit breaker occurring in rapid succession for rendering said operating means effective, said operating means when released biasing and holding said contacts open, and pumping means actuated by said circuit breaker for pumping fluid into said cumulative hydraulic means, said cumulative hydraulic means being self-resetting and having means for slowly discharging fluid pumped thereinto by said pumping means.

27. An automatic reclosing circuit breaker comprising a pair of contacts, electromagnetic means responsive to an electrical overload for separating said contacts, said circuit breaker being normally biased towards closed position and normally resetting itself after each opening operation, operating means for separating said contacts, said operating means having a part arranged in the path of travel of a portion of said circuit breaker for moving such portion to open said circuit breaker, said operating means being normally mechanically disconnected from said portion of said circuit breaker, and means responsive to a number of successive operations of said circuit breaker for causing said operating means to mechanically connect with said portion of said circuit breaker for biasing and holding said contacts open.

28. An automatic reclosing circuit breaker comprising a pair of contacts, electromagnetic means responsive to an electrical overload for separating said contacts, said circuit breaker having a movable portion movable when said contacts are moving to open position, said contacts being normally biased towards closed position, operating means for separating said contacts, said operating means having a portion arranged in the path of travel of said movable portion and normally mechanically disconnected from said movable portion and adapted when released to engage said movable portion to open said circuit breaker, restraining means for restraining the action of said operating means, cumulative hydraulic

means responsive to a number of successive operations of said circuit breaker occurring in rapid succession for releasing said restraining means, said operating means when released biasing and holding said contacts open, and pumping means actuated by said circuit breaker for pumping fluid into said cumulative hydraulic means.

29. An automatic reclosing circuit breaker comprising a pair of contacts, electromagnetic means responsive to an electrical overload for separating said contacts, lock-out means normally occupying an inoperative position for locking said circuit breaker in open position, said electromagnetic means normally separating said contacts independently of any motion of said lock-out means, means including cumulative hydraulic means responsive to a number of successive operations of said circuit breaker occurring in rapid succession for causing said lock-out means to move to lock-out position, and pumping means actuated by said circuit breaker for pumping fluid into said cumulative hydraulic means, said cumulative hydraulic means being self-resetting and having means for slowly discharging fluid pumped thereinto by said pumping means.

30. An automatic reclosing circuit breaker comprising a pair of contacts, electromagnetic means responsive to an electrical overload for separating said contacts, lock-out means normally occupying an inoperative position for locking said circuit breaker in open position, said electromagnetic means normally separating said contacts independently of any motion of said lock-out means, means including cumulative hydraulic means responsive to a number of successive operations of said circuit breaker occurring in rapid succession for causing said lock-out means to move to lock-out position, pumping means actuated by said circuit breaker for pumping fluid into said cumulative hydraulic means, said cumulative hydraulic means being self-resetting and having means for slowly discharging fluid pumped thereinto by said pumping means, and manual means for resetting said lock-out means.

31. An automatic reclosing circuit breaker comprising a pair of contacts, electromagnetic means responsive to an electrical overload for separating said contacts, said contacts being normally biased towards closed position, lock-out means biased towards lock-out position for locking said circuit breaker in open position, latch means for restraining said lock-out means, cumulative hydraulic means responsive to a number of successive operations of said circuit breaker occurring in rapid succession for releasing said latch means, and pumping means actuated by said circuit breaker for pumping fluid into said cumulative hydraulic means.

32. An automatic reclosing circuit breaker comprising a pair of contacts, electromagnetic means responsive to an electrical overload for separating said contacts, said contacts being normally biased towards closed position, lock-out means biased towards lock-out position for locking said circuit breaker in open position, latch means for restraining said lock-out means, cumulative hydraulic means responsive to a number of successive operations of said circuit breaker occurring in rapid succession for releasing said latch means, pumping means actuated by said circuit breaker for pumping fluid into said cumulative hydraulic means, and manual means for resetting said lock-out means in latched position.

33. An automatic reclosing circuit breaker comprising contact means, electromagnetic means

responsive to an electrical overload for opening said contact means, said contact means being normally biased towards closed position, time delay means for delaying the closing of said contact means, lock-out means for locking said circuit breaker in open position, said lock-out means normally occupying an inoperative position, and means independent of said time delay means and responsive to a number of successive operations of said circuit breaker occurring in rapid succession for moving said lock-out means to operative position.

34. In an automatic circuit interrupter, the combination with a switch normally biased toward closed circuit position and current controlled means for automatically moving said switch to open circuit position under predetermined current flow, of mechanical mechanism for moving said switch to open circuit position independently of said current controlled means, means independent of any portion of said current controlled means for biasing said mechanism for operation of said switch, a latch holding said mechanism against switch operating movement, said switch being movable to open position by said current controlled means independently of said mechanism, and releasing means for said latch subject to successive switch opening movements by said current controlled means for releasing said latch after a number of said successive movements of said switch.

35. In an automatic circuit interrupter, the combination with a switch normally biased toward circuit closed position and current controlled means for automatically moving said switch to open circuit position under predetermined overload conditions, of automatic switch operating mechanism normally held inoperative, said switch being movable to open circuit position by said current controlled means independently of said automatic switch operating mechanism, means actuated from said current controlled means for the release of said mechanism subsequent to a number of switch opening movements by said current controlled means, and means independent of any portion of said current controlled means for biasing said automatic switch operating mechanism towards switch opening movement.

36. An automatic reclosing circuit breaker comprising a pair of contacts, said circuit breaker being permanently biased towards closed position, electromagnetic means for temporarily opening said circuit breaker upon the occurrence of an electrical overload, normally restrained operating means for overcoming the permanent bias of said circuit breaker to prevent automatic closing of said circuit breaker, biasing means biasing said operating means more heavily than the bias of said circuit breaker, and means responsive to a number of successive operations of said circuit breaker for releasing said operating means.

37. An automatic reclosing circuit breaker comprising a pair of contacts, said circuit breaker being permanently biased towards closed position, electromagnetic means for temporarily opening said circuit breaker upon the occurrence of an electrical overload, normally ineffective operating means for overcoming the permanent bias of said circuit breaker to prevent automatic closing of said circuit breaker, biasing means biasing said operating means more heavily than the bias of said circuit breaker, and means responsive to a number of successive operations of said circuit breaker for rendering said operating means

effective to overcome the bias of said circuit breaker to hold said circuit breaker open.

38. In an automatic reclosing circuit interrupter, separable contacts, said contacts being biased closed to automatically reclose said contacts after a circuit interrupting operation, overload-responsive means for separating said contacts and including a member movable in response to overloads a predetermined amount before causing separation of said contacts, fluid dashpot means associated with said member whereby said contacts are opened only a predetermined time after said member is moved by said overload-responsive means, fluid means actuated in response to operation of said actuating member to be advanced the same predetermined amount in response to each circuit interrupting operation, and means positioned to be engaged by said fluid actuated means only when advanced a predetermined greater amount in response to a predetermined number of closely successive circuit interrupting operations for maintaining said contacts separated.

39. In an automatic reclosing circuit interrupter, cooperating contact means one of which is mounted for movement into and out of engagement with the other of said contact means, an actuating sleeve movable in response to overloads a predetermined amount before causing separation of said contacts, a cylindrical guide in which said sleeve is slidably mounted to form fluid time delay means for actuating said contacts a predetermined time after initiation of movement of said sleeve, said movable contact means being biased into engagement with said cooperating contact means to automatically reclose said contacts after a circuit interrupting operation, fluid operated lockout means adapted when advanced a predetermined amount from a normal position to prevent reengagement of said contact means, and fluid pumping means operable by said sleeve adjacent the end of its contact opening movement to advance said lockout means an amount less than said predetermined amount whereby said contacts are locked in an open circuit position in response to a predetermined number of circuit interrupting operations thereby.

40. In an automatic reclosing power circuit breaker, separable contacts, means unaffected by normal loads on the circuit through said breaker but responsive to overloads for causing separation of said contacts, means for automatically closing said contacts in response to a circuit interrupting operation, said overload responsive means having a part movable a predetermined amount in a circuit interrupting operation before said contacts separate, means for delaying movement of said part with an inverse time-current characteristic to delay separation of said contacts accordingly, means for causing said time delay means to retard automatic closing of said contacts, and means actuated by said time delay means so as to be responsive to a predetermined number of closely successive circuit opening operations for preventing automatic closing of said contacts.

41. In an automatic reclosing circuit breaker, separable contacts, means responsive to predetermined electrical conditions for causing separation of said contacts, said contacts being biased into engagement independently of said condition responsive means to automatically reclose said contacts after a circuit interrupting operation at a rate solely determined by said bias, time

delay means adapted to be mechanically associated with at least one moving part of the breaker for delaying opening of said contacts for a predetermined time after the occurrence of said predetermined conditions, and for delaying closing movement of said contacts a predetermined time after a circuit interrupting operation, and means actuated in response to one of the delaying operations of said time delay means during each opening and closing cycle of breaker operation so as to be responsive to a predetermined number of closely successive operations of the breaker to thereafter prevent automatic closing of the breaker contacts.

42. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, said movable contact being subjected to a biasing force sufficient to reclose the circuit at least as soon as it reaches full open circuit position, latch means for automatically detaining said movable contact against movement at an open circuit position against said reclosing bias, time delay means operated during a circuit interrupting operation for determining the time said detaining means is effective after which said time delay means releases said latch means and said biasing force is effective to reclose the contacts, and the circuit closing movement of said cooperating contact being solely influenced by the aforesaid biasing force.

43. In an automatic circuit recloser, a relatively fixed contact, a cooperating contact mounted for movement into and out of engagement with said fixed contact, overload-responsive means for causing movement of said movable contact away from said fixed contact to effect a circuit interrupting operation, said movable contact being subjected to a biasing force sufficient to reclose the circuit at least as soon as it reaches full open circuit position, latch
